Watson E. Coleman Attorney

UNITED STATES PATENT OFFICE.

CHARLES E. KENNEDY, OF ANTHONY, KANSAS.

FASTENING DEVICE.

Application filed August 29, 1921. Serial No. 496,277.

To all whom it may concern:

Be it known that I, CHARLES E. KENNEDY, a citizen of the United States, residing at Anthony, in the county of Harper and State 5 of Kansas, have invented certain new and useful Improvements in Fastening Devices, of which the following is a specification, reference being had to the accompanying drawings.

- 10 This invention relates to certain improvements in fastening devices and has relation more particularly to a device of this general character especially designed and adapted for use in connection with envelopes of a 15 jacket type, and it is an object of the invention to provide novel and improved fastening means of this type whereby the envelope may be conveniently and effectively maintained in closed or folded relation.
- 20 Another object of the invention is to provide a novel and improved fastening means which may be readily affixed or secured to an envelope and which embodies members supported for sliding movement and operating 25 in a manner to hold the envelope in a folded or closed arrangement.

The invention consists in the details of construction and in the combination and arrangement of the several parts of my invention 30 proved fastening device whereby certain important advantages are attained and the device rendered simpler, less expensive and otherwise more convenient and advantageous for use as will be hereinafter more fully 35 set forth.

The novel features of my invention will hereinafter be definitely claimed.

In order that my invention may be the better understood, I will now proceed to 40 describe the same with reference to the accompanying drawings, wherein:

Figure 1 is a view in elevation illustrating a fastening device constructed in accordance with an embodiment of my invention;

45 Figure 2 is a sectional view taken substantially on the line 2—2 of Figure 1;

Figure 3 is an end elevational view of the device as illustrated in Figure 1; and

50 Figure 4 is a view in perspective of the fastening device detached.

As disclosed in the accompanying drawings, A denotes an envelope of a jacket type and which embodies the panels or flaps 1 adapted to be folded in overlying relation, said envelope being of a style particu-

larly adapted for use for containing legal documents or similar papers.

My improved fastening means embodies an elongated plate B, preferably of metal, and of a length substantially equal to the width of the envelope A. The plate B, when applied, is positioned adjacent the outer margin of an end flap or panel 1 and the end portions of said plate B are provided with the laterally disposed wings 2 through which are disposed clamping eyelets 3 or the like for holding the plate B in applied position said wings 2 preferably extending inwardly of the coacting flap or panel 1.

The opposite longitudinal marginal portion of the plate B at its central part is provided with a relatively long and laterally directed wing 4 through which is directed a clamping eyelet 5 or the like whereby, the central portion of the member B is effectively held in applied position upon the flap or panel 1.

The inner longitudinal marginal portion of the member B between the wings 2 is provided with a flange 6 overlying the member B and the opposite longitudinal marginal portion of the member B at opposite sides of the wing 4 and extending from said wing to the outer ends of the member B is provided with the inwardly directed flanges 7, said flanges 6 and 7 affording guideways for the endwise movable fastening members 8.

Each of the fastening members 8 comprises an elongated body portion slidably engaged within the trackways afforded by the flanges 6 and 7 and extending beyond a side of the adjacent flap or panel 1. The outer end of the body of the fastening member is provided with an inwardly directed flat plate or hook 9 which, when the envelope is folded or closed, overlies, upon inward movement of the fastening member, the outer panel or flap of the folded or closed envelope, whereby said envelope is effectively maintained in such arrangement.

The inner end of each of the fastening members 8 is provided with an outstanding flange or returned portion 10 whereby the requisite endwise movement of the fastening members 8 is materially facilitated.

In order to strengthen or reinforce the plate or hook 9, the outer end portion thereof is provided with corrugations 11.

110

From the foregoing description it is thought to be obvious that a fastening device constructed in accordance with my invention is particularly well adapted for use by reason of the convenience and facility with which it may be assembled and operated, and it will also be obvious that my invention is susceptible of some change and modification without departing from the principles 5 and spirit thereof and for this reason I do not wish to be understood as limiting myself to the precise arrangement and formation of the several parts herein shown in carrying out my invention in practice except as hereinafter claimed.

I claim:

1. In combination with an envelope comprising flaps adapted to be folded into overlying relation, a plate secured to the outer 20 marginal portion of an end flap and provided with guideways, said plate being of a length to extend substantially entirely across the end flap, and elongated fastening members slidably engaged within said guideways 25 and extending beyond opposite sides of the envelope, the outer end of each of said fastening members being provided with an inwardly directed plate adapted, when the fastening member is moved inwardly, to 30 overlie the folded flaps of the envelope to hold said envelope in closed relation.

2. In combination with an envelope comprising flaps adapted to be folded into overlying relation, a plate secured to the outer 35 marginal portion of an end flap and provided with guideways, said plate being of a length to extend substantially entirely across the end flap, and elongated fastening members slidably engaged within said guideways 40 and extending beyond opposite sides of the envelope, the outer end of each of said fastening members being provided with an inwardly directed plate adapted, when the fastening member is moved inwardly, to 45 overlie the folded flaps of the envelope to hold said envelope in closed relation, each of said fastening members being provided at its inner end portion with an outstanding operating member.

3. In combination with an envelope comprising flaps adapted to be folded into overlying relation, a plate secured to the outer 55 marginal portion of an end flap and provided with guideways, elongated fastening members slidably engaged within said guideways and extending beyond opposite 60 sides of the envelope, the outer end of each of said fastening members being provided with an inwardly directed plate adapted, when the fastening member is moved in-

wardly, to overlie the folded flaps of the envelope to hold said envelope in closed relation, the opposite end portions of said member being provided with laterally directed wings extending inwardly of the envelope, and means associated with said wings for securing the member to the coacting flap of the envelope.

4. In combination with an envelope comprising flaps adapted to be folded into overlying relation, a plate secured to the outer 70 marginal portion of an end flap and provided with guideways, elongated fastening members slidably engaged within said guideways and extending beyond opposite 75 sides of the envelope, the outer end of each of said fastening members being provided with an inwardly directed plate adapted, when the fastening member is moved inwardly, to overlie the folded flaps of the 80 envelope to hold said envelope in closed relation, the opposite end portions of said member being provided with laterally directed wings extending inwardly of the envelope, means associated with said wings for 85 securing the member to the coacting flap of the envelope, the central portion of said member being provided with a wing, and means associated with said last named wing for securing the same to the adjacent flap 90 of the envelope.

5. In combination with an envelope comprising flaps adapted to be folded into overlying relation, a plate secured to the outer 95 marginal portion of an end flap and provided with guideways, elongated fastening members slidably engaged within said guideways and extending beyond opposite sides of the envelope, the outer end of each of said fastening members being provided with an inwardly directed plate adapted, when the fastening member is moved inwardly, to overlie the folded flaps of the envelope to hold said envelope in closed relation, the opposite end portions of said 100 member being provided with laterally directed wings extending inwardly of the envelope, means associated with said wings for securing the member to the coacting flap of the envelope, the central portion of said member being provided with a wing, and means associated with said last named wing for 105 securing the same to the adjacent flap of the envelope, said last named wing being disposed in a direction away from the first 110 named wings.

In testimony whereof I hereunto affix my signature.

CHARLES E. KENNEDY.
